UNITED STATES PATENT OFFICE.

DARIEN W. DODSON, OF WILKES-BARRÉ, PENNSYLVANIA.

TYPE-WRITING MACHINE.

SPECIFICATION forming part of Letters Patent No. 438,724, dated October 21, 1890.

Application filed March 30, 1887. Serial No. 232,944. (No model.)

To all whom it may concern:

Be it known that I, DARIEN W. DODSON, a citizen of the United States, residing at Wilkes-Barre, in the county of Luzerne and State of Pennsylvania, have invented certain new and useful Improvements in Type-Writing Machines, of which the following is a specification.

This invention relates to that class of typewriters (recently invented by me) in which the type-wheels have independent orbital and axial rotary movements, and in which the mode of printing the character is by rolling the type therefor on the material to be printed, while said type-wheel has both of said movements.

The principal object of my present invention is to provide a type-writing machine of that class in which the type shall be inked immediately before the act of printing therewith, thereby producing superior work, and in which the carriage shall be automatic in all its movements, thereby relieving the operator of much care and labor. For these purposes and to provide improved means for performing the various functions necessary or convenient to the practical operation of the machine the invention consists in the improvements and combinations hereinafter more fully set forth.

In the drawings accompanying, and forming a part of this specification, Figure 1 is a top view, on a reduced scale, of a type-writer embodying my improvements. Fig. 2 is a front elevation of the same. Fig. 3 is a rear elevation drawn about full size. Fig. 4 is an elevation of the right-hand side of the machine, and Fig. 5 of the left-hand side, as seen in Fig. 1. Fig. 6 is a vertical transverse section as seen from the right-hand side of the machine. Fig. 7 is a horizontal section taken about in line *a a*, Fig. 6. Fig. 8 is a front view of the carriage including other parts at the rear side of the machine, the printing mechanism being removed to better show said parts. Fig. 9 is an end view of the carriage mechanism and the accessory parts, showing the same in their normal or working position. Fig. 10 is a similar view showing the same parts during the automatic return-movement of the carriage. Fig. 11 is another similar

view showing the position of the parts while the carriage is being moved in either direction by hand. Fig. 12 is a top or plan view of one of the latch-frames and details assembled thereon. Figs. 13 and 14 are vertical sections partially across the latch-frame in the line of key-lever 70, showing, respectively, said lever in two positions; and Figs. 15 and 16 are two similar views showing one of the latches in two positions, respectively. These four figures illustrate the operation of the latches and keys. Figs. 17 and 18 are two plan views of certain parts of the carriage and feed mechanisms and illustrate certain features of their operation. Fig. 19 is a view similar to Fig. 9, showing a modification of the construction of the carriage. Fig. 20 is a diagrammatic top view showing a type-wheel and its lines of movement. Fig. 21 is a similar view showing the starting-arm for said wheel shown in Fig. 20 and the lines of movement of said arm. Fig. 22 is a similar view showing the corresponding features of the stop-arm on the shaft of said wheel. These three views are supposed to be taken one below the other in the order named and the movements shown to be all simultaneous in their respective planes. Figs. 23, 24, and 25 are diagrammatic views illustrating by three successive stages the operation of the starting-arm. Figs. 26 and 27 are a plan and side elevation, respectively, of a modification of the feed-wheel and gearing. Fig. 28 shows in plan view another modification, in a more simple form, of the feed mechanism. Fig. 29 is a top view of one of the type-wheel mechanisms, including a part of the turret carrying the same. Fig. 30 is a front elevation of the parts shown in Fig. 29. Fig. 31 is a side elevation of the same, drawn in projection to Fig. 30 and including the paper-guard. Fig. 32 is a top view of parts below line *f f*, Fig. 31. In these four figures the feed-pin is shown down and the type-wheel is turned partly around from its non-working position. Fig. 33 shows a part of Fig. 30 with the repeating mechanism in a different position. Figs. 34 and 34^a are diagrammatic top views, partly in section, illustrating the operation of the paper-guard. Fig. 35 shows a plan of the four type-wheels and the plan of designating the particular

types. Fig. 36 is a tabular list of the types and their respective characters.

Similar characters designate like parts in all the figures.

5 My improved type-writing machine consists of a frame-work supporting and carrying the several mechanisms, apparatuses, and details thereof; a printing mechanism provided with type-wheels and means for operating them; a 10 platen on which to print the paper; a latch mechanism and finger-keys operatively connected with the latches of this mechanism for indicating and controlling the operation of the printing mechanism; inking apparatus; 15 a paper-carriage; carriage-feeding mechanism actuating the carriage from the printing mechanism, and apparatus operating to make said carriage automatic in all its movements; and the nature of said machine is such 20 that some of said elements thereof may be materially changed as to their own construction and mode of operation without requiring any material change in other elements comprised in the same combination. For 25 instance, it is not a matter material to the printing mechanism whether one or another form of carriage-feeding mechanism is used; nor to the proper operation of said feeding mechanism whether one or another form of 30 repeating apparatus is used in the printing mechanism, or what devices shall be used to secure the proper automatic action of the carriage. The same is true, also, of the other elements above enumerated, and the following 35 detailed description of the machine is made to be read in the light of the principle thus illustrated.

The frame-work of the machine comprises or may comprise (besides a suitable table, as 40 A) the bed B, the bottom plate C, the carriage-track frame D, the upper bearing E, and the four latch-frames F, F', F'', and F'''.

The bed or main frame B, I prefer shall be made, substantially as shown, to have a chamber (having a cover K) for containing those 45 parts of the machinery which I denominate the "printing mechanism," and which I will next describe.

A revolute turret, designated in a general 50 way by T, is fitted to be freely revolved about an axis, which is usually and preferably a vertical axis. Said turret may properly consist of the central shaft 2, the upper disk 3, and lower disk 4, a pulley 6 being affixed 55 to shaft 2 for driving the turret by means of a belt. (Not shown.) The lower end of said turret-shaft is journaled in the lower bearing L and the upper end of said shaft in the upper bearing E in some suitable and well-known 60 manner. Carried in bearings in said disks there are a series of type-shafts (four in this instance) 5, 5', 5'', and 5''', all similar and set at equal distances from the turret's axis and from each other. Said shafts are herein referred to collectively as "shafts 5" and singly without choice as "shaft 5"—a mode of designation to be applied without further ex-

planation to various other duplicated details of the machine.

The type-wheel is a disk or wheel 8, of suitable material, (as hard rubber or metal,) having on its periphery a series of types, as I, except on one side where a few type-spaces should be left blank, as at 7. These wheels are or may be the same as the wheel E, described and claimed in Letters Patent of the United States No. 299,754, granted to me June 3, 1884. For the purposes of my present machine each of said wheels has thirteen utilized type-spaces and types for a different series of characters, so that the set of wheels has in all fifty-two utilized type-spaces, of which spaces fifty-one are for types and one for the "spacer." This will be understood by consulting Figs. 35 and 36. For properly starting revolving the said wheels and either of them to the exclusion of the others I provide each of the shafts 5, respectively, with a starting-arm 12, 12', 12'', and 12''', each set at a different height in the machine. (This 90 feature, however, is not of my invention.) For operating these arms to start their respective shafts I provide four corresponding tiers of similar reciprocating wheel starters or latches J, J', J'', and J''', which are adapted 95 to be interposed into the orbital path of said arms, respectively, and to engage with and start the same after the manner illustrated in Figs. 23, 24, and 25, showing successive steps of this operation. The movement of the starting-arm itself during the printing operation is illustrated in Fig. 21, in which the lines 160 161 represent the hypocycloidal path of said arm during the first and second revolutions, respectively, of shaft 5, the corresponding movements of the type-wheel being similarly shown in Fig. 20 and those of the stop-arm in Fig. 22. In these and other dia- 100 grammatic figures 45 is the axis of the turret, 46 the type-wheel orbit, and 47 the start- 105 ing-arm orbit—the path of the end of said arm when the shaft 5 is not revolving in its bearings. The line 48 indicates the type- 110 circle, this being a circle just circumscribing the types on one wheel, and the line 50 115 is the type-path, a circle circumscribing the type-circles of all the type-wheels. The latches J in each tier are individually designated by a numeral prefix, as 1^J, 2^J, up to 13^J, in regular order from the first to the 120 last latch of the series. The corresponding 125 types I on wheels 8 are individually designated by corresponding prefixes, the respective sets of types on separate wheels being distinguished by index-points, as in the case of the tiers or latches. The normal non- 130 working position of the starting-arm 12 relative to its orbit is shown in Fig. 23. To start the shaft 5, (the turret being continuously revolving,) one of the latches, as 1^J, is interposed within the orbital path 47 of said arm, as in said Fig. 23, and on the arrival of the arm engages with the outer end thereof, as also shown in this said figure. As the arm 12 stands in

its idle position forward of the radial line 49, when started revolving it acts, as in Figs. 24 and 25, after the manner of a toggle-joint to push back the starting-latch J. Thus when 5 the latch is once thrown in, as in Fig. 23, it is automatically returned as soon as (and not before) it has done its work.

The wheel starter or latch J consists, or may consist, of a flat slide or bolt fitted to have a 10 reciprocating movement in a slot or groove 60, Figs. 15 and 16, in the latch-frame F and under the cap 55. The latch is thrown forward (toward the right hand in Fig. 16) by a spring 56, contained in the frame, and which 15 acts through the sliding pin 57 against a projection 58, formed on the latch, said movement of the latch being limited by some suitable stop, as 59, formed thereon and striking against some fixed part, as cap 55, of the machine. At the outer end of slot 60 there is a 20 catch 62, immediately above a rabbet 61, formed in the latch-arc G of said frame F. A spring 63, having hook 64, is fixed to the latch at 65 and is adapted to engage with 25 catch 62 for holding back said latch, as in Fig. 15. The frame F has two segmental rims 66 67, Figs. 12, 13, and 14, of which the first is called the "fulcrum-rim" and the second the "guide-rim." The key-levers 70 lie in guiding-slots 68 69, formed in said rims, respectively. Said levers 70 are usually made of thin 30 sheet-steel of spring temper. At its outer end it is furnished with a finger-key 72, and at the other end 71 is adapted to serve as a tripping-rod or tripping-bar for unhooking the 35 latch-spring 63. The key-lever is normally held in the position shown in Fig. 13, with the key up and the working end 71 down, by some suitable and well-known form of spring—as, 40 for instance, the coiled wire spring 75, which is fixed in frame F at 74 and bearing down on the lever at 73. A suitable cover, as plate 16, is provided to protect the key-levers in the uppermost latch-frame F. As will be seen from 45 the plan view, Fig. 12, the key-levers stand about crosswise to the direction of motion of their respective latches. This position is preferred because the keys are thereby brought 50 into convenient and more symmetrical location in front of the turret and because it is necessary that the working end 71 of said levers shall stand substantially crosswise to said latch movement; but it is not necessarily at right angles thereto. The reason for this 55 requirement lies in the mode of operation of this latch mechanism, which is as follows: The latch being pushed back and hooked and the key being up, as in Figs. 13 and 15, the mechanism is ready for use. The operator now 60 presses down on the key 72, thereby raising the end 71 of lever 70, which end stands under hook 64 of spring 63. This operation lifts said hook until it clears catch 62, when the spring 65 56 throws the latch J forward, as in Fig. 16, the hook 64 now being above catch 62 and wholly forward of the outer face of said catch, as shown in this figure. During said upward

movement of end 71 said end bears with an elastic pressure against the outer face 76" of the latch-arc G and just below the rabbet 61; 70 but on the forward movement of hook 64 the end 71, being suddenly relieved of the resistance of spring 63, flies up and springs into the rabbet 61 and (when the operator releases the key) rests on the shoulder 76', as 75 in Figs. 14 and 16. Suppose now that the latch is next forced back to be hooked in its first position. It is evident that hook 64 will strike the lever and push end 71 out from the rabbet 61, and this whether or not the key has been released. If such is the case, then 80 the end 71 will immediately be thrown down, as in Figs. 13 and 15; but if not said end will stand up until the key is released. In any case, therefore, the proper and instant return 85 of the latch does not depend on nor is it affected by the position of the key. This is in fact the operation of said parts independently of said rabbet, the particular utility of which lies in this: The key 72 when pressed down may be pressed down instantly, as by a blow, or slowly and steadily, as by a gradually-increasing force. In the latter case (and if the latch shall be instantly returned) it is 90 possible to hold the lever end 71 with its upper edge exactly in the plane of the top of catch 62. The result of this will be to prevent the hooking of catch 64 on the return of said latch J, and thus to repeat the single operation of the printing mechanism and print 95 the same character twice in succession. In practice the danger of this improper action is sufficiently overcome by means of the construction described. The ledge 76' is set below catch 62 by a distance which is slightly 100 less than the vertical width of lever end 71, so that the sudden release of said end by the sudden movement of hook 64 allows said part 105 71 to catch on said ledge. This effectually prevents the operator maintaining (except, perhaps, intentionally) that nice adjustment 110 of the key-lever necessary to cause said repetition of the printing operation.

It is considered necessary in practice, in order to produce a quality of printing satisfactory to the public, to ink the type for the character to be printed after the selection of and immediately before the printing of such character; and to gain this result I have constructed my improved type-writer to use a 115 type-wheel that is twice-revolving—that makes two revolutions on its own axis each time started. This mode of operation of said 120 wheels I obtain in the present instance by means of a mechanical movement similar to that described and claimed in the joint application of D. W. Dodson and F. H. Richards, Serial No. 219,327; but I may use therefor other devices adapted to start and revolve in such manner a shaft or wheel. Said mechanical movement, (including what I designate 125 as the "repeating apparatus,") as shown in the drawings, consists of the following parts, all fully shown and described in the aforesaid

application, Serial No. 219,327, namely: The segmental gear 10, whose teeth 17 mesh with the teeth of the rack or internal gear 15, (herein not fully shown,) which is concentric to the 5 orbit of said gear 10, and which is or may be the same rack that is described and claimed in United States Patent No. 390,097, granted to F. H. Richards September 25, 1888, the starting-arm 12, for engaging with the latch 10 to start said shaft 5, the pinion 13, fixed on shaft 5, the stop-arm 14, for bringing said shaft to rest after making the required number of revolutions on its own axis, as illustrated in Fig. 22, the segmental stop-rim 36, 15 fixed on the frame, for intercepting said stop-arm, gear 26, twice the diameter of and driven from gear 13 and pivotally supported on the turret, cam 27 on said gear and operating the sliding sleeve 23 on the shaft 5, one or more 20 teeth 20, carried on said sleeve, and thus actuated by said cam to be interposed at and held for the proper time in the circuit of teeth 17, and the sliding detent-pin 31 with its spring 32. Of these several parts said 25 sleeve has a detent-cam 24, which actuates the arm 19 of a lever 21, whose other arm 22 bears on the upper end of said pin 31. Immediately above the detent-cam face 25 there is a circular disk or rim 28, which when this 30 cam is lowered runs against the long arm 19 of said lever 21, and thus prevents the upward movement of detent-pin 31 until the sleeve 23 is again raised by cam 27. Thus said detent-pin when once it is thrown down 35 remains down during nearly two revolutions of the type-shaft. The object of this arrangement is twofold: first, to prevent the operation of the detent until the end of the second revolution of said shaft, and thus avoid unnecessary resistance to the operation thereof, 40 and, second, to provide for the feeding of the paper-carriage, as hereinafter more fully described, during the time in which the type-wheel is passing from the inking to the printing points. By constructing and using the 45 detent-pin to act also as a feed-pin for operating the feed-wheel said pin (properly constructed) becomes the principal element of one part of the carriage-feeding mechanism, and a very simple mechanical device is thus 50 made to serve two important and distinct functions in the machine.

The inking apparatus consists, essentially, of an ordinary inking-pad or a roller or the 55 like placed adjacent to that part of the type-path which is at a distance corresponding to one revolution of the type-wheel backward from the printing-point. In the drawings said apparatus consists of the roller 30, which 60 is fitted to turn freely on a stud 29, fixed in or to some part of the frame-work. The roller 30 may be constructed to operate in either one of two ways, as may be preferred: First, the roller may be made of absorbent material and be saturated with ink, after the usual manner of inking the ribbons of type-writers; second, said roller may be made of non-ab-

sorbent material (preferably somewhat elastic) and supplied on its outer surface with ink by means of inking appliances, after the 70 manner of the ink-distributing apparatus of printing-presses. In either case the type rolls against said roller or pad with sufficient pressure to be properly inked. The manner in which a given type, as 11, is brought first to 75 the inking-roll and then to the printing-point is shown in Fig. 20, in which lines 162 163 represent the hypocycloidal path of said type during the first and second revolutions, respectively, of the type-wheel. 80

The platen, against which the paper is printed, consists of a suitable block supported adjacent to the type-path at the printing-point. This block 80, I make of a slightly-elastic quality of vulcanized rubber; but various other materials may be used therefor. To facilitate placing paper in the machine and to free the sheet from resistance while the carriage makes its return-stroke, the platen should be supported and operated substantially as follows: A printing post or bracket 76 stands in a fixed position rearward of the printing-point. This post is or may be affixed to or be a part of the track-frame D, as shown, or it may be otherwise supported on 90 the frame-work. Said post carries a platen-carrier or printing-slide 77, to the front end of which is affixed the platen 80. The slide 77 is adapted to have a limited reciprocating movement in said post or bracket, this movement being derived from the carriage or from the carriage-driving mechanism by means of a lever 78, pivoted to said post at 79, as hereinafter more fully explained. The forward movement of the upper end of that lever is 105 limited by a stop at 81. Said upper end has a pressure-adjusting screw 82, which acts through pin 83 against spring 84, contained in slide 77. This slide projects rearward of 110 said lever and has a position-adjusting screw 85, (formed hollow for admitting screw 82,) which bears against said lever for the purpose of adjusting the normal (forward) position of said slide to bring the platen in proper relation to the type-path. 115

The carriage of my improved machine has, in a general sense, the leading features of ordinary type-writer carriages—that is to say, it has a longitudinal movement forward step by step from right to left, and has paper-holding rollers whereby the paper may be fed up for printing successive lines; but my said carriage differs from the carriages of ordinary type-writers, in that it is constructed and organized in itself and in connection with 120 its feeding and accessory apparatuses to have an automatic return movement, to automatically feed up the paper during such return movement, and to actuate the platen at the beginning and end of such movement. These 125 and other improvements will be understood from the following detailed description of a preferred form of this part of my machine. 130

The track-frame D, hereinbefore mentioned,

has on the upper edge thereof the carriage-track 90, and the carriage-frame H has two bearings 86 87, fitted to engage and slide on said track. The carriage also has or may 5 have a rocking movement, which is provided for by making said track rounded, as shown, or by means of other construction permitting such movement. At its lower side said frame H carries a rack R, whose teeth 88 mesh with 10 the teeth of gear P. A suitable rib or red 89, fixed to the rack or other part of the carriage, is fitted to slide in the forked end 91 of lever 78 for the purpose of operating the platen from a lateral movement of said rack. Said 15 gear and rack constitute a part of the carriage-driving mechanism, (the same as described and claimed in my application, Serial No. 232,945,) whereby the carriage is made automatic in all its movements. This mechanism has, besides said detachable or disengaging gearing, a rack-switching apparatus 20 consisting of the following parts or some mechanical equivalent therefor. A stud or "shuttle" 105 is attached to the carriage in 25 a normally-fixed relation to the rack thereon. This shuttle stands when the rack is in mesh with gear P at the rear side of a rib-shaped "shuttle-guide" 107 on the plate 99. Two switch-arms 110 and 112, similar in form and 30 function, are carried on said plate and are oppositely disposed to said guide. These arms are shown to be carried on the ends of springs 109 and 111, respectively, which are fixed to the plate 99 at 113 and 115. Said 35 arms are also set inclined, about as shown, and are yieldingly held (by said springs or otherwise) against the ends of guide 107. The outer end of the arm 110 or 112, however, has preferably a short part 114 about 40 parallel to guide 107, for a purpose hereinafter explained. The hooks 108 are designed (one of them) to serve as a stop to limit the return-stroke of the carriage when no other stop is provided or when some other stop 45 than the driving-pinion is deemed necessary; but in practice such hook may be dispensed with and some other device substituted therefor, if any substitute be required. The operation of this switch apparatus as 50 thus constructed is as follows: The several parts being situated as illustrated in Figs. 8 and 9, the proper forward movement of gear P moves forward the carriage to its position in Fig. 17, until the shuttle 105, reacting 55 against guide 107, forces back arm 110 and rests between said guide and the straight part 114 of said arm, as here shown, so that said arm shall not at this moment exert any endwise force on the shuttle and carriage. A 60 slight additional forward movement of said carriage now carries said shuttle past said guide, and the spring-arm 110, bearing on said shuttle, carries back this and the rack, as shown at the left hand in Fig. 18 and in Fig. 65 10, thereby unmeshing or detaching the said rack and gear and permitting the carriage to be moved backward. This movement is pref-

erably accomplished by means of a return-spring, as commonly employed for moving the carriages of type-writers. On the carriage, 70 approaching the end of its return-stroke, the opposite arm 112 bears against the shuttle in the opposite direction, as shown by dotted lines at the right hand in Fig. 18, and at the end of said stroke forces the shuttle 105 past 75 said guide and the rack into mesh or engagement with gear P, after which the forward movement of the carriage may go on as before. Thus by means of this rack-switching apparatus or some other equivalent device 80 and the disengaging gearing the carriage becomes in a sense self-acting and will be automatically returned whenever its given forward stroke is completed, the extent of this stroke depending of course on the length of 85 guide 107. The lateral movement of the rack R carries laterally the rib 89, and thus operates through lever 78 and its connections to simultaneously move the platen 80, as herein-before-explained, so that said platen shall be 90 drawn back from the type-path on the forward movement of the rack, and vice versa. The operation of the carriage to throw back said platen also throws back the feed-rolls and the sheet of paper, which are hereinafter 95 described. For convenience in making comparison of the several parts of said switch apparatus, these parts are (excepting plate 99) herein designated by reference-numerals which are each greater by one hundred than 100 the corresponding ones in my said application, Serial No. 232,945. Thus 107 and 112 in this present application are 7 and 12, respectively, in that application. For effecting the return-stroke of the carriage I employ a return-spring of the kind usually used for the 105 same purpose in other machines having carriages of this class. Said spring is or may be contained within a drum 98, pivoted on frame D at 97. A strap 96, wound on drum 110 98, is connected to the bearing 86, as shown, or to some other part of the carriage. The spring is supposed to be adjusted to the tension required for returning the carriage within a proper time. This time I consider to be 115 about one-half of a second; but it may be more or less, according to circumstances. On the end of track 90, I place a stop or buffer 92, for stopping the carriage at the end of the return-stroke and to relieve the hook 108 of 120 that duty. This buffer I make of vulcanized rubber or of other yielding material, so as to reduce the force and noise of the blow thereon. This blow, however, when the machine is in 125 all respects properly adjusted will be very slight, so that the buffer is considered useful chiefly as a safeguard.

The paper is held in place on the carriage and fed up by means of rollers situated above the platen, substantially in the usual manner. 130 The feed-roll 100 is journaled in the upwardly-projecting arms 94 95. The pressure-rolls 102 103 are supported on a rod 101, which is carried by spring-arms 104 106, that are attached

to said arms 94 and 95, respectively. These pressure-rolls are adjustably placed on said rod 101 to accommodate sheets of paper of various widths. Said adjustment may be effected in several ways; but I prefer placing the pressure-roll on a sleeve 93, fitting freely therein, which sleeve is set at any point on the rod by means of a set-screw 116. Above and back of the rollers I place a guard 117, fixed on the upper ends of arms 94 95, for supporting the sheet to exhibit the few lines last printed. This guard also in practice serves to tie together said arms, and thus strengthen the carriage. It is preferably made of thin steel metal, light and stiff. The feed-roll 100 has a knob 118, or other part, for like purpose, whereby it may be turned in either direction by hand, and an ordinary ratchet-wheel 119, whereby it may be turned forward automatically. This is or may be effected by an apparatus as follows: A lever 120, journaled on the shaft of roll 100, has a pawl 121, engaging with said ratchet. That lever is operatively connected by a rod 122 to another angle-lever or rock-shaft 124, which is pivoted to or in the carriage-frame at 123. A spring 125, connected to said part 124, serves to throw up rod 122, whose upward movement is limited by a stop 126. A stop 128 is fixed to frame D in such position as to strike the arm 127 of rock-shaft 124 just before the carriage completes its return-stroke, as shown by dotted lines in Fig. 3. This draws down rod 122 and turns roll 100 to feed up the paper. By combining together the said parts in such manner as here described an important result is gained—namely, the considerable momentum acquired by the carriage during its return-stroke is to a large extent converted into useful work and applied to the turning of the feed-roll, which, being under pressure, requires considerable power for that purpose, and this work being subtracted from that momentum leaves little force to be expended against the buffer 92. A consequence of this action is to reduce the otherwise considerable tendency of the carriage to rebound, and thus to reduce the concussion and noise of the re-engaging gearing and of the switch apparatus. These results are evidently of great value in type-writing machines, which should be in operation as nearly silent as practicable. It should be noted in this connection that the carriage in my machine returns substantially free of restraint, whereas in other type-writers it is moved by hand, and thus kept under control.

It has been stated that the shuttle 105 is attached to the carriage in a "normally-fixed" relation to the rack R. By this is meant that the relative positions of said shuttle and rack do not change during the ordinary operation of the machine; but it is sometimes necessary in practice to temporarily disengage the gearing for the purpose of moving the carriage by hand either forward or backward. To permit this, said shuttle is movably at-

tached to the carriage, and is specially arranged to have (by means of a shifting device) a limited stroke toward and from said rack. One suitable and convenient apparatus or shifting device for this purpose is constructed and arranged as follows: The shuttle 105 is formed on the lower end of an arm 130, which is pivoted to the carriage-frame H at 129. This arm has a slot 131, in which works the crank-pin 132, that is fixed in the crank-arm 133 on rock-shaft 134. Said crank is bifurcated, and incloses the sides of arm 130 to furnish a firm guide for the same. Shaft 134 is carried in bearings 136 137 on frame H, and is operated by means of the lever 135 and connecting-rod 138 from the arm 139 of the movable thumb-piece 140, which piece is pivotally supported on the journal of roll 100 or on some other part of the carriage. A fixed piece 141 is provided, so that said thumb-piece may be moved by clasping these two pieces after the ordinary manner of operating thumb-catches on levers in other classes of machinery.

The mode of operation of this last-described apparatus is illustrated by Fig. 11. By closing together the thumb-pieces 140 141 pin 132 is raised in slot 131 from its position in Fig. 9 to that in Fig. 11. This draws the shaft 134 and by this rack R toward arm 130, and holds the carriage in the same position as in Fig. 10. As shown in Figs. 9 and 10, the arm 133 stands substantially at right angles to said arm 130, so that the action of the switch apparatus does not tend to move crank-pin 132 either up or down; but said pin normally stands down on the bottom of the slot 131 at what may be called its "dead-center," and is arranged to move up, as shown in Fig. 11, thereby disengaging the gearing, as aforesaid. This being done, the operator may slide the carriage in either direction at will, and on releasing said thumb-pieces permit pin 132 to be thrown down (by the weight of the parts or by a spring not shown) and re-engage the gearing. It will be noted that this apparatus is to be used only when the shuttle is rearward of guide 107, as in Figs. 9 and 11.

The frame H, constituting the largest portion of the carriage, is preferably shaped, as is well shown in Figs. 9, 10, and 11, to form a paper-holding receptacle or pocket Q to contain the sheet of paper to be printed. This sheet is supposed be represented in edge view by the solid line 150, the lower part thereof being rolled up, as at 149, in said pocket. The upper edge of said sheet is passed up between the feed and pressure rolls in front of platen 80. When the carriage stands as in Fig. 9, its driving-gearing being in mesh, this platen stands forward, as also shown in this figure, so that the type-wheel 8 may roll on the paper with a pressure sufficient to print the character; but when the carriage is rocked or swung into its position in Figs. 10 and 11 said platen is drawn back, as there shown, leaving a clear space between its face and the type-path. The

carriage being now moved in either direction on its track, the paper 150 is free to pass along in said space without liability of being touched by the type, even though the printing mechanism is being operated.

In some cases the carriage may be arranged not to have a rocking movement. One such modification is shown in Fig. 19. The carriage-frame H has in this case a rib 89", running in a notch or bearing in the frame of the machine, thereby preventing any working movement of said frame, except longitudinally. The rack R is made separate from said frame H and pivotally attached thereto at 143, and the shaft 134 is carried in bearings on the rack. The bar or arm 130 is connected to the carriage, and is operated therefrom as before.

In order to properly feed the carriage previous to the printing of the character selected, it is necessary, since the speed of the machine is ordinarily very rapid, to utilize for the feeding operation as much as possible of the distance between the successive type-wheels; and in order to properly ink the type for the character selected and to do so before the printing of such character the inking apparatus is set, as hereinbefore described, one revolution of the type-wheel backward in the type-path from the platen. Now, it so happens that in practice the distance in the type-path between the type-wheels successively used is or may be about equal (as shown in the drawings) to the distance between the inking apparatus and said platen, so that while one said wheel is passing from the inking apparatus to the platen the carriage may be feeding forward and only come to rest (or substantially so, for a slight movement is permissible) at just the moment before the said type reaches said platen, and that the following said wheel may begin to feed the carriage (for the character next to be printed) immediately after the said preceding wheel has printed the first character. Thus almost the whole time is or may be utilized for the relatively laborious operation of feeding the carriage by using therefor the time of the aforesaid one revolution which the type-wheel makes while passing from the inking apparatus to the platen. This result I accomplish by means of a carriage-feeding mechanism which comprises a feed-arm or feed-wheel (and gearing) that is situated (as to the orbital movement of said type-wheels) between said apparatus and said platen, and which is constructed to be operated by a feed-pin that is interposed in the path of the feed-wheel arms directly or indirectly by the type-wheel and at about the time of the starting revolving of said wheel—that is to say, on or soon after the starting revolving of a type-wheel on its own axis a cam or the like on or connected therewith throws down (interposes) the lower end of the feed-pin, as 31, into the horizontal plane of the said arm or arms, so that when said pin arrives at the orbital position of said part of

the carriage-feeding mechanism it will engage with or act on the feed-arm, and acting through this and its connections will feed the carriage. Said carriage-feeding mechanism comprises two parts, of which parts the one consists of the feed-pin, as 31, carried on the turret, and the means described for operating the same by or from the type-wheel, and of which parts the other consists (in its preferred form) in a feed-wheel having a fixed location in the machine and gearing operatively connecting the same with and to feed the carriage. This feed-wheel, which is designated in a general way by W, is shown and described, and a combination thereof with a feed-pin corresponding to pin 31 is claimed, in a separate application, Serial No. 227,855. As shown in the drawings of this application, said wheel has a series of five similar feed-arms N, set equidistantly from each other, and is pivotally supported on the frame of the machine by a stud or shaft 40, which carries a gear 41. This gear 41 meshes with an intermediate gear 42, which is fixed on the frame by a stud 43, and which drives the gear 44 on feed-shaft S, which shaft carries the feed-pinion P, adapted to mesh with and drive the rack R, carried on the paper-carriage. Some suitable detent, as 35, is employed to prevent the wheel W from backward movement. Of these several parts the shaft S, pinion P, and rack R are supposed to be the parts so designated in my application, Serial No. 232,945.

For actuating the pinion P, I have preferred to use the wheel W, because of the peculiar mode of operation thereof, in combination with the orbitally-moving feed-pin, which operation is fully described in my aforesaid application, Serial No. 227,855; but various modifications of this part of the carriage-feeding mechanism may be used in this machine as equivalents for the said preferred arrangement. One such modified apparatus is shown in Figs. 26 and 27. Here the shaft 40 is placed horizontally, and is connected to shaft S by bevel-gears 39. The feed-wheel V has a series of elongated cam-shaped arms 38, preferably shaped to be actuated by pin 31. Another modification, also an equivalent, as aforesaid, is shown in Fig. 28. In this arrangement a ratchet-wheel 37 is fixed on shaft S, and prevented from backward movement by the detent 33. The feed-arm, designated by U, is a single one and is pivoted to the frame at 51. The working-face 52 of said arm is shaped, substantially as shown, so that the feed-pin 31 shall readily actuate the arm and drive this from its position shown by solid lines to that indicated by dotted lines. A pawl 54, pivoted to the arm at 53, serves to actuate wheel 37 from the movement of said arm. It is to be supposed that the return movement of said arm is obtained by some spring and is limited by some stop, and that pawl 54 is held in contact with wheel 37 by a spring. (All not shown.)

While my machine is operative by using in the carriage-feeding mechanism only one feed-arm, as in Fig. 28, there is a distinct utility in the combinations specified of a feed-wheel having a series of such arms. With the single arm time must elapse between the successive feeding operations in which to allow the feed-arm to make its return-stroke. By using a suitable feed-wheel provided with a series of feed-arms properly proportioned and shaped one forward movement of the carriage may be begun almost or quite as soon as the preceding movement is completed, so that in practice and by this means the rapidity of the carriage movement may be greatly increased and the whole machine have, in effect, a correspondingly greater efficiency.

It is in practice very desirable not only that the machine be so organized that the carriage movement shall be completed just before the printing act, but also that the reciprocating movement of the carriage shall be so timed relative to said printing act that when at the end of a line a character is printed at all it shall be fully printed, and so timed that the return-stroke of the carriage or the backward movement of the platen shall not begin during such act and thereby cause said character to be blurred or otherwise imperfectly printed.

In combining together and timing the several parts concerned in securing that result it is evidently necessary to consider the weight, inertia, and elasticity of said parts and the speed and rapidity of succession of the movements of those parts. Having due regard to these several features and considering also that the full backward movement of the platen (said movement being derived from the lateral movement of the rack) must be completed substantially during the very brief period of time between the departure from said platen of one type-wheel and the arrival there of the next, it is found that the rack should be disengaged at almost the completion by the carriage of its forward movement—that is, the last forward movement of the carriage will be nearly completed, as in Fig. 17, when the shuttle 105 passes the end of the guide 107, and when the type selected has approached nearly to the platen 80 the rack-switching apparatus will then begin to act on the rack (to throw this out of mesh) just before the moment of the printing act, while the type-wheel 8 is in about the orbital position shown in said Fig. 17; but, owing to the inertia aforesaid of the rack and connected parts and the high velocity of the type-wheel, (the turret should be revolving about two hundred or more turns per minute,) the force of said apparatus (when properly proportioned) can only begin to effect such disengagement before the type will have passed the platen, as in Fig. 18. Owing to the weight of the parts to be moved and their consequent inertia, the said disengage-

ment cannot become perceptibly advanced before the type-wheel, owing to its high orbital velocity, will have printed the character 70 and passed on from the printing-point. In Fig. 17 the feed-pin 31 has substantially completed a given forward movement of the feed-wheel W, having moved arm N from the position N', this movement being completed before wheel 8 reaches the platen, but not until just after shuttle 105 (shown by solid lines in this figure) passes the end of guide 107. After this last event and before said shuttle has perceptibly moved toward the position 80 105' thereof, Fig. 17, the type-wheel strikes the paper on platen 80, which then recedes, as in Fig. 18, before the arrival of wheel 8'.

To properly appreciate the practical utility and value of that peculiar combination 85 and arrangement of the printing and carriage mechanisms, it should be understood that the turret may sometimes be driven at a speed of five hundred revolutions per minute, so that the time between the printing 90 acts (four wheels being used) may not be greater than the one thirty-second part of a second, and the time between the release of the shuttle 105 and the printing act less than the one one-hundred-and-fiftieth part of a 95 second. This very brief moment of time is found in practice to be less than is required to properly overcome the inertia of the rack and connected parts, while the one thirty-second part of a second is ordinarily time enough 100 to effect the aforesaid disengagement and throw back the platen.

Another improvement embodied in my machine consists in a paper-guard having a lateral movement toward and from the platen 105 and operated from the printing mechanism. This device in a preferred form is most fully shown in Figs. 31, 34, and 34^a. The guard consists of a spring or yielding post 180, fixed at its lower end, and of which the upper end 110 stands normally clear of the platen, as shown in Fig. 34. The type-wheel has thereon (or on the shaft thereof) a guard-cam 182, corresponding in its general shape to the shape of the type-wheel. When the type-wheel has 115 only an orbital movement, as in Fig. 34, the cam 182 lies wholly within lines 183; but when said wheel has at the same time an axial rotary movement the said cam rolls against the inner surface 184 and pushes forward the 120 guard, as in Fig. 34^a, before the type printed from reaches the platen. The chief advantage of this improvement is that the paper 125 150 is pushed back on each side of the platen, so that the types adjacent to the type printed from cannot touch the paper, if this is wrinkled and uneven, which is frequently the case, especially where several copies are made by "manifolding" at one time.

The construction and mode of operation in 130 detail of the several mechanisms having now been described, I will next explain the operation of using the machine as a whole.

A sheet of paper 150 is first placed in the

machine, as explained in connection with Figs. 9, 10, and 11. The operator next seizes handles 140 141 and places the carriage in position for printing the first letter of a given line. The turret being now (or previously) set in constant rotation at suitable speed in the direction shown by the arrows, the finger-key for a required character is struck, thereby unhooking one of the latches—as, for instance, the latch 1¹, Fig. 21. This latch, by striking arm 12 of shaft 5 in position X, starts the type-wheel revolving, as in Fig. 20, and the gearing described continues such movement to bring the corresponding type 1¹ first onto the inking-roll 30 and then against the paper on platen 80 and until the stop-arm 14 is intercepted by the stop-rim 36. In the meantime, however, the feed-pin 31 has actuated the feed-wheel and gearing to feed forward the carriage one letter-space and to complete such feed movement before the character is printed, as hereinbefore more fully described. These operations are repeated, using such keys (including the spacer) as required by the matter to be printed, until the given line is finished, when the carriage returns automatically, as set forth, and takes up its position ready for beginning the next line, having fed up the sheet on its return movement, as before explained. Thus it will be seen that the ordinary operation of the machine involves only the supplying of the paper and the proper manipulation of the keys.

The type-wheel, as specified in the claims, is supposed to consist of a disk or type-wheel proper, having thereon the types, some suitable shaft or stud for revolvably supporting said wheel proper, and some suitable arm or the like on said shaft or wheel, and serving to start the same revolving by engagement with the wheel-starters. So far as these separate details are concerned in the general operation of the machine as a whole, they are functionally one element, however distinct they may be considered as to the operation of some particular mechanism comprised in the machine.

As used in this specification in respect of the carriage and carriage-feeding apparatus and as generally used herein the word "reciprocating" is a generic term which includes the specific terms "linear reciprocating" and "rotary reciprocating."

In some cases the platen 80, together with its supporting devices, may be dispensed with and the roll 100 set lower down, as at 165, Fig. 10, so that the paper will be printed on said roll as a platen. In those of my claims in which a platen is specified as "an element" such element may be either of the fixed form 80 or the roll form thereof, as may be preferred, and both of these forms are intended to be covered in combination by the said claims.

It will be understood that this machine, and especially the several mechanisms and details thereof, is capable of modification in

various ways and degrees other than the ways described after the manner of machines in general within the scope and limits of my invention.

With regard to the carriage-feeding mechanism described, as it is not broadly my invention, I do not claim herein a carriage-feeding mechanism consisting, essentially, of a feed-arm operated from the printing mechanism and connected to the carriage by means of gearing, and a switch apparatus operating to disengage said gearing on the completion by the carriage of its forward stroke and to re-engage the same on the completion by the carriage of its return-stroke.

Having thus described my invention, I claim—

1. The combination, in a type-writer having a platen and inking apparatus, of the revolvable turret, a type-shaft provided with a type-wheel and carried on said turret at a distance from the axis thereof, shaft-starting devices, substantially as described, for starting and revolving said shaft, and a repeating mechanism, substantially as described, for continuing the movement of said shaft through two revolutions thereof, whereby a particular type is brought first to the inking apparatus and afterward to the platen, substantially as described.

2. The combination, in a type-writer of the class described having a revolvable turret and a twice-revolving type-wheel mounted on said turret at a distance from the axis thereof, of wheel-starters and a platen, and an inking apparatus located between said starters and platen and at a distance from said platen corresponding to one revolution of said type-wheel, all substantially as described, and for the purpose specified.

3. The combination, in a type-writer of the class described and with the twice-revolving type-wheel having an orbital movement and having types located on the periphery thereof at fixed circumferential distances from each other, of a platen, an inking apparatus situated at the distance in the type-path and from said platen of one revolution of said wheel, and wheel-starters situated at fixed distances apart in the orbit of the wheels, which orbital distances correspond to said circumferential distances, whereby a given wheel-starter acts to start said wheel to first ink the character whose circumferential position on said wheel corresponds to the orbital position of said wheel-starter and to then print on said platen the character so inked, substantially as described, and for the purpose specified.

4. The combination, in a type-writer of the class described and with the twice-revolving type-wheel thereof having an orbital movement, of wheel-starters, a platen located, as to the direction of the orbital movement of said wheel, at a printing-point forward of said starters, an inking apparatus between said starters and said printing-point and one revolution of said wheel distant from said point,

a paper-carriage for supporting and feeding the paper past said point, carriage-feeding mechanism located as to the orbital movement of said wheel between said inking apparatus and printing-point and operatively connected with said carriage, and a feed-pin carried with the type-wheel in its orbital movement and adapted to be thrown by or on the starting of said wheel into position for actuating said feed mechanism during the passage of said wheel from the inking apparatus to the printing-point, all substantially as described, and for the purpose specified.

5. The combination, in a type-writer and with a revolute type-wheel mounted on a revolute turret at a distance from the axis of said turret, of a paper-carriage, and a feed mechanism consisting of two parts, of which parts the one consists of a feed-arm having a fixed location in the machine and operatively connected to feed said carriage, and of which parts the other consists of a reciprocating feed-pin carried on said turret and actuated from said type-wheel, the whole being organized and coacting to interpose, on the starting revolving of said type-wheel on its own axis, the said feed-pin in the path of said arm, all substantially as described.

6. The combination, in a type-writer and with a revolute type-wheel mounted on a revolute turret at a distance from the axis of said turret, of a paper-carriage, and a feed mechanism consisting of two parts, of which parts the one consists of a series of feed-arms constituting a feed-wheel and having a fixed location in the machine, said arms being operatively connected to feed said carriage, and of which parts the other consists of a reciprocating feed-pin carried on said turret and actuated from said type-wheel, the whole being organized and coacting to interpose, on the starting revolving of said type-wheel on its own axis, the said feed-pin in the path of said feed-wheel arms, all substantially as described.

45 7. The combination, in a type-writer of the class described and with the paper-carriage and the revolute turret thereof, of a feed-arm operatively connected to feed said carriage, and a feed-pin carried on said turret and adapted to have a sliding movement, whereby it may be interposed in and withdrawn from the path of said arm, all substantially as described.

55 8. The combination, in a type-writer, of a revolute turret, a paper-carriage, a feed-arm operatively connected by gearing, substantially as described, to feed said carriage, a feed-pin carried on said turret and actuated from the printing mechanism, and a switch apparatus, substantially as described, that operates to disengage said gearing on the completion by the carriage of its forward stroke and to re-engage the same on the completion by said carriage of its return-stroke, substantially as and for the purpose shown.

9. The combination, in a type-writer, of a

revolute turret, a reciprocating carriage, a feed-pin carried on said turret and actuated from the printing mechanism, an intermittently and forwardly revolving gear receiving its motion from said feed-pin, a laterally-moving rack-bar on said carriage, and rack-switching apparatus constructed and operating to disengage said rack from said gear on the completion by the carriage of its forward stroke and to re-engage the same on the completion by the carriage of its return-stroke, substantially as and for the purpose specified.

10. The combination of the reciprocating carriage carrying the laterally-movable rack, the feed-gear, the laterally-movable shuttle on said carriage, and shifting devices, substantially as described, adapted to be operated to move said rack relative to said shuttle, all substantially as described, and for the purpose specified.

11. The combination, in a type-writer and with the revolute turret thereof, and with a revolute type-shaft carried on said turret, of means, as shaft-starters, gearing, and a stop, for starting, revolving, and stopping said type-shaft, a reciprocating feed-pin carried on said turret, and a cam moving simultaneously with said type-shaft and which on the starting of said wheel throws said feed-pin into its working position, all substantially as described, and for the purpose specified.

12. The combination, in a type-writer, of a reciprocating carriage having a rocking movement, a feed-gear, a rack on said carriage, adapted to mesh with said gear, and switch apparatus, substantially as described, operating to disengage said rack and gear on the completion by the carriage of its forward stroke and to re-engage the same on the completion by said carriage of its return-stroke, all substantially as described.

13. The combination, in a type-writer, of a platen having a normally-fixed position and adapted to have a reciprocating movement, a reciprocating carriage for carrying the material to be printed in front of said platen, detachable feed-gearing, substantially as described, operating to move forward said carriage, switch mechanism, substantially as described, operating to disengage said gearing on the completion by said carriage of its forward stroke and to re-engage the same on the completion by said carriage of its return-stroke, and connections operating to throw back said platen on the disengagement of said gearing and throw forward the same on the re-engagement of said gearing, all substantially as described, and for the purpose specified.

14. The combination, in a type-writer and with the printing mechanism and movable platen thereof, of the reciprocating carriage, and feed mechanism, substantially as described, having a feed-wheel located back of the printing-point, whereby the carriage is fed forward and released prior to the print-

- ing of the last character of a line, all substantially as described.
15. The combination, with the reciprocating carriage and with the rack carried on said carriage and constructed and arranged to have a lateral movement, of the platen and connections actuating said platen from the operation of said rack, all substantially as described.
- 10 16. The combination of the rocking carriage, platen-slide, lever 78, having a stop, as 81, and connecting said carriage and slide, and means, as adjusting-screws, for adjusting said slide, substantially as and for the purpose set forth.
- 15 17. The combination, with the rocking carriage, of a platen, feed-rolls on said carriage above the platen, and connections from the carriage to the platen, operating to throw back said platen simultaneously with the rocking of the carriage to throw back said rolls, substantially as described.
- 20 18. The combination, in a type-writer and with the carriage thereof, of the slotted shuttle-arm 130, the crank-arm engaging said shuttle-arm, and connecting devices, substantially as described, for operating said crank-arm by hand, all substantially as described.
- 25 19. The combination, in a type-writer and with the revoluble turret thereof, of a revoluble type-shaft, a movable feed-pin, and a cam actuating said feed-pin, said shaft and feed-pin being arranged to have simultaneous movements and the whole being organized and coacting to project the feed-pin on the starting of said shaft, all substantially as described.
- 30 20. The combination, in the latch mechanism of a type-writer, of the reciprocating latch having the spring-hook 64, the catch 40 62, the rabbet 61, and the key-lever constructed and arranged to unhook the latch and rest in said rabbet, all substantially as set forth, and for the purpose specified.
- 35 21. The combination, in the latch mechanism of a type-writer, of a reciprocating latch having the spring-hook, and a key-lever having the elastic end 71, said lever being situated crosswise to the line of movement of said latch, substantially as shown and described.
- 40 22. The combination, with the latch-frame F, having slots for the latches and having guide-rim 67, and fulcrum-rim 66, of the latches in said slots, and the key-levers in slots in said rims, substantially as shown and described.
- 45 23. The combination of a shaft, as 5, the sliding sleeve 23, having cam 24 and rim 28, and lever 21, substantially as shown and described.
- 50 24. The combination, with the type-wheel having a guard-cam, of the movable paper-guard constructed and arranged to be operated by said cam prior to the printing act, all substantially as set forth.
- 55 In testimony whereof I have signed my name to this specification, this 23d day of March, 1887, at Hartford, State of Connecticut, in the presence of two subscribing witnesses.
- 60 DARIEN W. DODSON.
- Witnesses:
- FRANCIS H. RICHARDS,
GEO. A. REYNOLDS.
